FRUIT PACKER'S STAND

James Augustus Byington, Orlando, Fla.

Application July 24, 1937, Serial No. 155,551

5 Claims. (Cl. 214—44)

The invention relates to fruit packers' stands and has for its object to provide a stand having supporting means for a box in which fruits are packed, and means carried by the stand and adapted to cooperate with a stationary member for tripping the box supporting means for depositing the same onto a conveyor.

A further object is to provide a stand with pivoted box supporting arms held in raised position at an elevation above the elevation of the conveyor, and held in said elevated position by latching means which latching means is released when the stand is forced towards the conveyor for depositing the filled box on pivoted brackets carried by the conveyor, and normally held in raised position above the conveyor, thereby allowing the stand and its arms to be removed from the conveyor and the filled box to be deposited on the conveyor chains by a manual tilting of the tiltable brackets through a movement of the box, thereby obviating the necessity of operator or packer lifting the box and placing the same on the conveyor.

A further object is to provide spring means cooperating with the pivoted bracket for normally maintaining the same in raised position under the weight of box until there is a manual tilting operation by pressure applied on the box in the direction of travel of the conveyor.

A further object is to provide means whereby the box supporting arms may be adjusted in relation to each other for accommodating the stand to different size boxes.

A further object is to provide wheel supporting means for the stand whereby it may be moved towards or away from the conveyor, for the box loading and unloading operations.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a top plan view of the stand, showing the same in connection with a conventional form of conveyor.

Figure 2 is a view in elevation of the outer side of the stand, showing the upper portion thereof and the conveyor.

Figure 3 is a vertical longitudinal sectional view through the conveyor, showing the tiltable

brackets in tilted position for depositing a box on the conveyor.

Figure 4 is a vertical transverse sectional view through the conveyor, showing the stand in relation thereto and in a position where a further movement towards the conveyor will deposit the box on the tiltable brackets.

Figure 5 is a vertical transverse sectional view through one of the adjustable arm carrying shafts and the sleeve carried thereby for adjusting the arms in relation to each other.

Figure 6 is a longitudinal sectional view through the sleeves, showing the adjustable arm carrying shafts therein.

Figure 7 is a detail view showing the latching means for holding box supporting arms in raised position and releasing said arms.

Referring to the drawings, the numeral 1 designates a conventional form of conveyor frame having longitudinal bars 2 on the upper sides of which are mounted conveyor chain channels 3, in which are longitudinally movable conventional forms of conveyor chains 4, and onto which the filled boxes which have been previously packed are deposited for conveying purposes, said boxes being designated by the numeral 5. Hingedly mounted at 6 between the bars 2 are the upwardly extending arms 7 of U-shaped tiltable brackets 8, which extend upwardly between the bars 2 and the conveyor chains, and terminate above the chains, and onto which boxes as they are filled are placed and supported spaced from the conveyor chains 4. U-shaped brackets 8 are normally held in raised position by means of contractile springs 9, anchored at 10 to the arms of the brackets and extending away from the direction of travel of the chains, and are anchored at 11 to the inner sides of the rails 3.

The rearward movement of the brackets 8 is limited by stops 12 carried by the inner sides of the rails, and the forward extreme movement of the brackets is limited by stops 13 carried by the inner sides of the rails, in the path thereof, and in positions where the pivotal points of the brackets will not pass across a straight line drawn between the spring anchoring points 10 and 11, hence there is no danger of a bracket being rendered inoperative by swinging to the extreme lower position. When the U-shaped brackets are in raised position, they will support a box 5 thereon until they are tilted by a longitudinal movement of the box in the direction of travel of the conveyor, which is in the direction of the arrow a, Figure 3.

In packing stands at present constructed, it

is necessary for the packer to lift the filled boxes and deposit the same on the conveyor, and this is a laborious operation. In the present device device there is no lifting of the boxes.

5 The packing stand proper comprises a base 14 which is supported on casters 15 of conventional structure, so the stand can be moved towards and away from the conveyor side. Extending upwardly from the base 14 are uprights 16 connected together by a cross bar 17. Rotatably mounted in bearings 18 in the upper end of the uprights 16 are axially aligned arm carrying shafts 19, which extend towards each other and are rotatably mounted in a sleeve 20, which has 10 formed integral therewith, or otherwise secured thereon the downwardly extending trip latches 21. Sleeve 20 is provided with bayonet slots 22 in which headed members 23 carried by the shafts move. These bayonet slots and headed members 15 allow shafts 19 to be extended for accommodating 20 the device to boxes of different lengths.

Secured to the outer ends of the shafts 19, which rotate in unison, are box supporting arms 24, which incline slightly upwardly, and on which 25 the box rests during a packing operation, and the stand is away from the side of the conveyor, thereby allowing any other boxes moving on the conveyor to be conveyed and during which action the conveyed boxes will engage the various 30 brackets at the various packing stations, and swing the same downwardly until the box passes the bracket and at which time it will move to vertical position under the influence of its spring.

35 Rotatably mounted in bearings carried by the uprights 16 is a horizontal shaft 25, which is provided with latching discs 26. One side of the latching disc is provided with a recess 27, and the latching arm 21 extends downwardly and inwardly and terminates in a nose 28, which rides 40 on the periphery of the disc 26 for holding the arms 24 in raised position as shown in Figure 4. When the stand is pushed towards the conveyor and the arms 24 are over the conveyor, a trip arm 29 carried by shaft 25 is rocked in the direction of the arrow b, Figure 4, and disc 26 is rotated to a point where the latch arm nose 28 45 will enter the notch 27, thereby allowing the box supporting arms 24 to move downwardly, and the box to be deposited on the hinged brackets 8, and at which time the stand is withdrawn 50 from the conveyor to move the arms 24 from an overlying relation to the conveyor and then the packer imparts a longitudinal push on the filled box. This action will tilt the brackets 8 and 55 deposit the box on the conveyor chains. The above action is repeated as each box is filled and placed on the conveyor.

It will be noted that as the stand is pushed towards the conveyor, trip arm 29 engages the side of the conveyor for the tripping operation. Trip arm 29 is provided with stop arm 30, which 60 limits the pivotal action of the trip arm and maintains the same in position. If desired a spring 31 may be provided for positively returning the trip arm to normal position for resetting the arms 24, as it is obvious the operator, before putting the empty box on the arms 24 could raise the arms 24 slightly and spring 31 would rotate disc 26 to its proper position so the latching nose 28 would engage the periphery thereof, and notch 27 65 would be in position for the next unloading operation.

70 From the above it will be seen that a fruit and vegetable packer's stand is provided, which

is simple in construction, the parts reduced to a minimum, and one wherein it will not be necessary for the packer to lift boxes as they are filled, and deposited on the conveyor.

The invention having been set forth what is 5 claimed as new and useful is:

1. The combination with a conveyor having tilttable receptacle supporting means for supporting a receptacle above the conveyor until tilted, of a truck movable towards and away from one 10 side of the conveyor, said truck having receptacle supporting arms at an elevation above the tilttable receptacle supporting means on the conveyor, latching means carried by the truck and cooperating with the arms for maintaining said 15 arms elevated above the tilttable receptacle supporting means and latch releasing means carried by the truck and positioned to engage the side of the conveyor when the truck is moved towards the conveyor when the receptacle is supported 20 above the tilttable receptacle supporting means on the conveyor.

2. A conveyor loading truck for loading a conveyor from the side thereof, said truck comprising a movable frame movable towards and away 25 from the side of the conveyor, said frame having pivoted receptacle supporting arms at its upper end above the conveyor, latching means carried by the frame and cooperating with the arms for maintaining the same elevated above the conveyor and latch control means carried by the frame and positioned to engage the side of the conveyor for releasing the latch control means of the arm when the truck reaches its limit of movement towards the conveyor and the receptacle supporting arms are disposed above the conveyor.

3. A receptacle supporting truck adapted to be moved towards the side of a conveyor for depositing receptacles on the conveyor, said truck comprising a frame, a rock shaft in the upper end of said frame, receptacle supporting arms carried by said rock shaft and adapted to support receptacles at an elevation above the top of the conveyor and to extend across the top of the conveyor when the truck is moved towards the side of the conveyor, latching means for maintaining said receptacle supporting arm in raised position and latch releasing means carried by the truck and positioned to engage the side of the conveyor 45 as the truck reaches the limit of its movement towards the conveyor for allowing the receptacle supporting arms to move downwardly for depositing a receptacle on the conveyor.

4. A device as set forth in claim 3 wherein 55 the latching means comprises a rockable shaft carried by the truck, notched arms rigidly mounted on said shaft, latching arms carried by the receptacle supporting arm shaft and engaging the cams, said latching arms having members 60 slidably engaging the cam surfaces of the cams and receivable within the notches thereof upon release of the latching means.

5. A device as set forth in claim 3 wherein the rock shaft in the upper end of the frame is 65 formed from axially aligned sections each of which carries a receptacle supporting arm, a sleeve mounted on said axially aligned sections and bayonet connections between the shaft sections and the sleeve, whereby the receptacle supporting 70 arms may be adjusted in relation to each other.

JAMES A. BYINGTON.
